UNITED STATES PATENT OFFICE.

WILLIAM F. SCHACHT, OF GOSHEN, INDIANA.

SINK-STOPPLE.

No. 901,195.

Specification of Letters Patent.

Patented Oct. 13, 1908.

Application filed December 13, 1907. Serial No. 406,359.

To all whom it may concern:

Be it known that I, WILLIAM F. SCHACHT, of Goshen, in the county of Elkhart and State of Indiana, have invented certain new 5 and useful Improvements in Sink-Stopples; and I hereby declare that the following is a full, clear, and exact description thereof, reference being had to the accompanying drawings, which form part of this specification.

10 This invention is a novel stopple or stopper especially designed for use in ordinary house sinks wherein the outlet is customarily covered by a strainer, and is not intended ordinarily to be closed.

15 The object of the invention is to provide a reinforced rubber stopple which can be placed over the screen and will close the perforations and prevent the escape of water so that the sink can be filled with water if desired and used as a pan or tub for washing 20 dishes, clothes and the like.

25 The invention is also useful as a stopple for ordinary wash-basins and tubs in houses, and as a substitute for the metallic or hard rubber stopple commonly employed.

The object of the present invention is to provide a non-metallic rubber disk-like stopple which shall be imperforate and which will be flexible and reinforced in center and 30 easily manipulated and which can be readily molded complete and without any metal parts or attachments that would tend to corrode the rubber and wear the stopple.

35 The invention consists in the novel construction of such stopple, as will be fully understood from the following description in connection with the accompanying drawings which illustrate the stopple, and the mode of making the same.

40 Figure 1 represents a top view of the complete stopple. Fig. 2 is an edge view thereof; and Fig. 3 is a central cross section of the stopple. Figs. 4 and 5 are views illustrating the mode of making the stopple.

45 The stopple comprises a circular disk-like body portion 1, having a central integral knob 2, on one side connected with the body portion by an integral stem 2a.

50 The marginal part 1a of the body 1, is entirely of rubber and is very flexible or pliable so that it will lie close against the surface on which the stopple is laid. The marginal portion of the stopple is that part lying out-

side of the dotted line $\alpha-\alpha$ in Fig. 1. In practice this marginal portion is about one 55 inch in width on a stopple about four inches in diameter.

The central portion 1b of the body, lying within the marginal portion, is stiffened or reinforced internally by a layer of canvas, 60 or other suitable textile material, indicated at 3 in the drawings. This canvas is embedded in the rubber in the process of making the stopple and extends up into the stem and head 2 as indicated in Fig. 3, so as to 65 stiffen the stem and the head, and this canvas greatly increases the durability of the stopple and prevents collapse thereof under 70 water pressure and facilitates removal of the stopple.

The stopple can be manipulated by hand by grasping the knob 2, or if desired, a chain or cord can be attached to the stem under the knob.

The structure of the stopple will perhaps 75 be more fully comprehended by a brief explanation of the preferred mode of making the same, which is illustrated in Figs. 4, 5 and 6.

In making the stopple I take a piece of 80 sheet rubber 1^x which may be cut into disk form if desired, and place thereon a smaller disk of canvas 3^x, and lay thereover a second disk of rubber 2^x, see Fig. 4. These are then placed in a mold, (Fig. 5) which comprises 85 a lower portion A, resting upon a base B, and an upper member C. The opposed faces of the parts A and C are recessed to correspond exactly to the exterior form of the stopple to be produced. The lower mold 90 A preferably has a removable central part formed of two opposite similar pieces a, a, which are recessed in their adjacent faces, so that when the parts a are fitted together, the recesses therein together correspond in 95 contour to the contour of the knob and stem of the stopple.

The assembled sheets 1^x, 2^x, 3^x, of rubber and canvas are laid upon the mold A and then the mold 1 placed thereover and compressed thereagainst so as to force the central portion of the rubber and canvas down into the part a of the mold (see Fig. 5) and form the knob, and while the mold is fastened in this manner upon the contained rubber, it is subjected to sufficient heat to

vulcanize the rubber; whereupon the mold may be opened and the complete stopple removed.

It will be seen that part of the canvas is extended or directed by the pressure into the stem and knob of the stopple and it forms a tough stiffening but flexible reinforced connection between the knob and the stopple proper.

10. If desired, the mold C may have a slight circular recess e in its central portion which will produce a circular projection or thickening of rubber, on the under side of the stopple, as indicated at 1^e in the drawings.
15. The stopple thus formed is very strong, flexible and durable; it will form a watertight closure over the sink strainer, and the suction and pressure thereon are amply sufficient to keep the stopple in place.
20. The rubber and the stiffening fabric 3 form, when vulcanized, a practically homogeneous body, and there will be no tendency of the fabric 3 to separate from or split the rubber. As no metal is employed in the 25 structure of the stopple or embedded therein, there is nothing contained in the stopple tending to corrode or disintegrate it and it being imperforate, is not liable to puncture or be torn by any inserted metallic connections, and it is perfectly noiseless and will 30 not scrape or deface any surface with which it comes in contact.

Having described my invention what I

claim as new and desire to secure by Letters Patent is:

35

1. A non-metallic rubber stopple comprising a disk of rubber having an integral knob and stem connected centrally to one side thereof and having a piece of fabric embedded in its central portion, said fabric extending into the stem.

40

2. A stopple comprising a disk of rubber having an integral knob on one side and centrally thereof, and having a sheet of fabric in its central portion embedded in the rubber, said fabric extending into the knob and said disk having a marginal portion of pure rubber projecting beyond the edges of the sheet.

45

3. A rubber stopple composed of upper and lower sheets of rubber, an interposed disk of fabric, the sheets of rubber projecting beyond the edges of the disk to form a flexible marginal portion of pure rubber, and the fabric and rubber sheets being 50 formed into a central knob on one side, and at the center of the stopple, the sheets and disk being vulcanized, substantially as described.

55

In testimony that I claim the foregoing as 60 my own, I affix my signature in presence of two witnesses.

WILLIAM F. SCHACHT.
